The ornamental design for a plunger rod having retaining anchors, as shown and described.

DESCRIPTION

FIG. 1 is a perspective view of a plunger rod having retaining anchors in accordance with the present invention;

FIG. 2 is an enlarged partial perspective view of the plunger rod having retaining anchors of FIG. 1;

FIG. 3 is a top plan view of the plunger rod having retaining anchors of FIG. 1;

FIG. 4 is a bottom plan view thereof;

FIG. 5 is a front elevation view thereof;

FIG. 6 is a rear elevation view thereof; and,

FIG. 7 is a right side elevation view thereof, with the left side view being a mirror image.

The dash dot lines in FIGS. 1 and 2 are included for the purpose of illustrating an enlarged area and form no part of the claimed design.
